UNITED STATES PATENT OFFICE.

PETER RABIDEAU, OF PLATTSBURG, NEW YORK.

SHADE-BRACKET.

971,214.

Specification of Letters Patent. Patented Sept. 27, 1910.

Application filed January 31, 1910. Serial No. 541,066.

To all whom it may concern:

Be it known that I, PETER RABIDEAU, a citizen of the United States of America, and resident of Plattsburg, in the county of Clinton and State of New York, have invented certain new and useful Improvements in Shade-Brackets, of which the following is a specification.

This invention relates to curtains, shades and screens and particularly to a class thereunder known as shade roller brackets.

An object of this invention is to produce a shade roller bracket and in conjunction therewith, a novel mounting or support for said bracket whereby the said bracket may be adjusted transversely of the window or window frame in order to increase or diminish the distance between two of said brackets, one on each side of the window.

20 A further object of the invention is to provide for raising or lowering the shade roller by inverting the brackets.

A still further object of this invention is to provide a shade roller bracket, a mounting therefor, and in conjunction therewith friction producing devices for holding the brackets in different positions of adjustment on the mounting, the said friction producing devices being yieldable under proper 30 manipulation in order to relieve the friction when the bracket is to be adjusted.

With the foregoing and other objects in view, the invention consists in the details of construction and in the arrangement and 35 combination of parts to be hereinafter more fully set forth and claimed.

In describing the invention in detail, reference will be had to the accompanying drawings forming part of this specification 40 wherein like characters denote corresponding parts in the several views, in which—

Figure 1 illustrates a fragment of a window frame in elevation with the invention applied thereto; Fig. 2 illustrates a sectional view on the line 2—2 of Fig. 1; Fig. 3 illustrates a perspective view of the friction device inverted compared with the position it occupies in Fig. 1; Fig. 4 is a detail in elevation of the companion to the shade bracket 50 shown in Fig. 1; and Fig. 5 is a detail of the screw eye 11.

In Fig. 1, I show the mounting for the bracket as comprising a frame formed of a strip of metal bent to produce the parallel bars 4 and 5 with a connection 6 extending vertically when the mounting is applied to

a window frame. At the junction of one of the bars and the vertical portion 6, I produce a loop 7 forming an eye 8 which may receive a portière hook or the like (not shown) or I may secure the vertically disposed portion by a staple or eyelet 11. The parallel bars 4 and 5 are supported by screw eyes 10 and 11 respectively and it is the purpose of the inventor that the bracket mountings shall remain as a fixture thus obviating the destruction or injury of window frames after such a mounting has been once applied in a building. A shade bracket is applied for each bracket mounting and the said 70 brackets are duplicated throughout except for the direction of the coil and the bearings that receive the shade roller. They will differ according to the configuration of the spindles of the shade rollers, as will be 75 understood by those skilled in the art.

In producing the shade bracket, I employ a length of wire which is shaped to form a coil 12 intermediate its length which coil is applied to the bar 4 and is preferably slid- 80 able thereon without undue friction. One end of the material forming the coil extends outwardly to form the arm 13 which terminates in a bearing 14 which may be of any contour necessary to accommodate the end 85 of the roller spindle as heretofore explained. The opposite end of the material forming the bracket is bent to form a seat 15 to receive the lower bar 5 as shown in Figs. 1 and 2 and near the extremity of that end in 90 which the seat is formed, I provide another seat 16 which is designed to receive a tension member. The tension member comprises a strip of spring metal having an arm 17 extending upwardly into engagement with the 95 rear surface of the coil 12 and an end bent to form a loop 18 which is seated in the recess 16 and a second loop 19 which encircles the bar 5 and is slidable thereon. The tension member has the two loops mentioned 100 for engagement with the bar and bracket and the said tension member bears against the said bar as shown in Figs. 1 and 2 and has its end or arm bent to lie back of the coil as stated. By this arrangement of parts, the 105 depending portion of the bracket shown in Fig. 2 is forced into frictional engagement with the bar 5 on one side of said member whereas the tension member engages the bar on the opposite side thereof and the bracket 110 will be held against movement under ordinary conditions of use. By proper manipu-

lation, the bracket may be adjusted longitudinally of the bars but upon being released, the tension device will exert sufficient pressure to obviate accidental displacement of the said bracket, as will be obvious without illustration, that by removing the bracket from the rods 4 and 5, it may be inverted and replaced so that the coil 12 will be upon the rod 5 and the depression 15 upon the rod 4, thus lowering the bearings 14.

I claim:

1. In a shade fixture, a bracket mounting comprising bars, a bracket slideable longitudinally of the bars, and a tension device for holding the bracket in different positions of adjustment, said tension device being looped at its lower end and engaging with the corresponding end of said bracket and hooked over one of said bars.
2. In a shade fixture, a bracket mounting comprising a frame having parallel members, and a portion connecting said members, a bracket having a coiled section slideable on one of the members and an extension in slideable engagement with the other member, means for frictionally holding the extension in slideable engagement therewith, and a bracket arm forming a portion of said coil, said frictional holding means including a member having a looped lower end engaging the corresponding end of said bracket and hooked over one of said members.
3. In a shade bracket, a bracket mounting comprising parallel bars and an end connection therefor, a bracket comprising a length of wire coiled intermediate its length to receive one of the bars and having one of its ends producing an arm and bearing and the opposite end thereof in engagement with the other bar of the mounting, means for holding the said mounting and bracket

in frictional engagement, the said opposite end having a seat to receive the bar, and a tension device for frictionally coupling the bar and one end of the bracket.

45

4. In a shade fixture, a bracket mounting comprising parallel bars and an end connection therefor, a bracket comprising a length of wire coiled intermediate its length to receive one of the bars and having one of its ends producing an arm and bearing and the opposite end thereof in engagement with the other bar of the mounting, means for holding the said mounting and bracket in frictional engagement, the said opposite end having a seat to receive the bar, a tension device having loops for embracing a bar and the end of the bracket for retaining the same in frictional engagement.

50

5. In a shade fixture, a bracket mounting comprising parallel bars and an end connection therefor, a bracket comprising a length of wire coiled intermediate its length to receive one of the bars and having one of its ends producing an arm and bearing, and the opposite end thereof in engagement with the other bar of the mounting, means for holding the said mounting and bracket in frictional engagement, the said opposite end having a seat to receive the bar, and a tension device comprising an arm lying in engagement with a coil of the bracket and having double loops near its end for engaging the end of the bracket and the bar.

55

In testimony whereof I have hereunto affixed my signature in the presence of two witnesses.
